UNITED STATES PATENT OFFICE.

HENRY COHN, OF NEW YORK, N. Y.

PRINTING-FRAME.

1,108,707.

Specification of Letters Patent. Patented Aug. 25, 1914.

Application filed January 11, 1913. Serial No. 741,397.

To all whom it may concern:

Be it known that I, HENRY COHN, a citizen of the United States, and a resident of the city of New York, borough of the Bronx, in the county of New York and State of New York, have invented a new and Improved Printing-Frame, of which the following is a full, clear, and exact description.

My invention has for its object to provide a printing frame having upper and lower frame members, hinged at one end, there being a spring for raising a glass member relatively to the lower frame member, so that a print may be conveniently slid off the glass, the glass being normally held down, and in the lower frame member by back members and clamps on the upper frame member. These back members are prevented from falling through the upper frame member by the hinges, connecting the back members when the upper frame is raised relatively to the lower frame member, the hinges extending laterally, and being adapted to rest on an inner flange on the upper frame member.

Additional objects of the invention will appear in the following complete specification, in which the preferred form of the invention is disclosed.

In the drawings similar characters of reference indicate corresponding parts in all the views, in which—

Figure 1 is a perspective view of the invention; Fig. 2 is an enlarged fragmentary plan view of the invention, with parts broken away to show the spring for raising the glass member; Fig. 3 is a front elevation of the invention; Fig. 4 is a sectional view on the line A—A of Fig. 2 with the printing frame closed; Fig. 5 is a similar sectional view, but with the printing frame opened, and with the upper frame member supported by the indicating means; Fig. 6 is a sectional view of the printing frame on the line 6—6 of Fig. 2; and Fig. 7 is a fragmentary sectional view showing the position of a holding screw as it is being turned to hold the rear of the glass in place.

By referring to the drawings it will be seen that a printing frame has a lower open frame member 5 with inner flanges 6, extending into the opening, these flanges 6 being spaced from the upper face 7 of the lower frame member 5. A glass member 8 is normally disposed on these flanges 6, a spring 9 being disposed on the forward flanges 6^a, which serves to hold the forward

end of the glass member 8 yieldingly upward, and at or above the plane of the upper face 7 of the lower frame member 5, so that a print disposed on a negative 10 supported by the glass member 8, may be slid forwardly, and over the forward end of the lower frame member 5, and free from the printing frame. The rear of the glass member 8 is held down by a bent screw 8^a which 65 when in normal position has its head 8^b disposed against the rear of the glass member 8. To this lower frame member 6 there is hinged at the rear 11 an upper open frame member 12, this upper frame member 12 70 having at its sides inwardly extending flanges 13. Disposed in for closing the openings 14 in the upper frame member 12, there are two back members 15, which are hinged together by the hinges 16, as best 75 shown in Fig. 1 of the drawings. These hinges 16 extend beyond the sides of the back members 15, and over the flanges 13, so that the downward movement of the back members 15 relatively to the upper frame 80 member 12 is limited. The back members 15 are provided with the usual spring clamp members 17, which have ends 18, for engaging with the flanges 19 on the upper frame member 12. The bottom of the back 85 members 15 is covered with a soft material 20, in the usual manner.

When the printing frame is opened, as shown in Fig. 5 of the drawings, a piece of printing paper may be disposed on the negative 90 10, and the printing frame may then be closed, the back member 15 pressing the negative and the glass member 8 downward and against the resiliency of the spring 9, until the glass member 8 rests on the flanges 6. 95 The pressure against the glass member 8 then serves to force the back members 15 upward, and against the resiliency of the spring clamps 17, so that the hinges 16 will be raised above the upper plane of the 100 flanges 13. For holding the upper member 12 down on the lower frame member 5 I provide a clamp member 21, which is pivoted to a bracket 22 by a pin 23, these brackets 22 being secured to the upper frame member 105 12. The clamp member 21 has outwardly disposed catch members 24, for engaging the projections 25 on the lower frame member 5. The upper portion of the clamp 21 is held 110 yieldingly outward from the upper frame member 12, by a coiled spring 26 which is wound on the pin 23 between the outwardly

extending ends 22^a of the bracket 22, and which has a terminal 23^a pressing against the top of the clamp 21, and a second terminal 23^a pressing against the frame member 12.

When printing paper has been disposed on the negative 10, and the upper frame member 12 has been closed against the lower frame member 12, either one of the back members 10 15 may be opened by means of a spring clamp 17, so that the photographer may determine if the printing has been completed. When the printing is found to be completed, the back member 16 which has been opened 15 is again closed, and the forward end of the upper frame member 12 is freed from the forward end of the lower frame member 5, by pressing inwardly the upper portion of the clamp 21, which frees the catch members 20 24 from the projections 25, and as the upper frame member 12 is raised the spring 9 serves to raise the forward portion of the glass 8 so that the print on the negative 10 may be slipped forwardly and freed from 25 the printing frame.

Having thus described my invention, I claim as new and desire to secure by Letters Patent:

1. In a printing frame, an open frame member having an inner flange spaced from one face of the frame member, a glass member normally disposed on the flange, and a spring for raising an end of the glass member relatively to the frame member, so that 30 35 a print may be readily slid off the end of the glass member and the frame member.

2. In a printing frame, an upper open frame member, a lower open frame member hinged at one end to the upper frame member, and having an inner flange spaced from one face of the frame member, a glass member normally disposed on the flange, a spring for raising an end of the glass member relatively to the lower frame member, two back 40 45 members hinged together for closing the opening in the open frame member, the hinges extending over portions of the upper frame member to limit the downward movement of the back members relatively to the upper frame member, and means for holding the back member down relatively to the upper frame member.

3. In a printing frame, an open frame

member, two back members hinged together for closing the opening, the hinges extending over portions of the frame member to limit the movement of the back members relatively to the frame member, resilient clamps for holding the back members relatively to the frame member, and a second frame member for coöperating with the first frame member.

4. In a printing frame, an open frame member, two back members hinged together for closing the opening, the hinges extending over portions of the frame member to limit the movement of the back members relatively to the frame member, resilient clamps for holding the back members relatively to the frame member, a second frame member hinged at one end to the first frame member, and means for holding the other end of the second frame member against the first frame member.

5. In a printing frame, an open frame member, two back members hinged together for closing the opening, the hinges extending over portions of the frame member to limit the movement of the back members relatively to the frame member, resilient clamps for holding the back members relatively to the frame member, a second open frame member hinged at one end to the first frame member, means for holding the other end of the second frame member against the first frame member, a glass disposed in the opening in the second frame member, and resilient means for holding one end of the glass at or above the upper plane of the second frame member.

6. In a printing frame, an open frame member having an inner flange, a glass member normally disposed on the flange, a member for holding one end of the glass member down, a spring on the flange for holding the other end of the glass member yieldingly upward and a back member hinged to the open frame and normally pressing the glass member down.

In testimony whereof I have signed my name to this specification in the presence of two subscribing witnesses.

HENRY COHN.
